UNITED STATES PATENT OFFICE.

THOMAS WELLINGTON HOGSETT, OF EDRAY, WEST VIRGINIA.

MOTOR.

SPECIFICATION forming part of Letters Patent No. 328,678, dated October 20, 1855.

Application filed March 30, 1855. Serial No. 160,685. (No model.)

To all whom it may concern:

Be it known that I, THOMAS W. HOGSETT, a citizen of the United States, residing at Edray, in the county of Pocahontas and State 5 of West Virginia, have invented a new and useful Improvement in Motors, of which the following is a specification, reference being had to the accompanying drawings.

This invention relates to motors especially 10 designed for operating churns, washing-machines, and the like; and it has for its object to provide simple, inexpensive, durable, and efficient means for this purpose, which may be operated with ease and facility, and have 15 considerable power, is not liable to get out of order, and will work with very little friction, and at no great expenditure of force.

With these ends in view the said invention consists in the peculiar construction and combination of parts, as will be hereinafter set forth, and particularly pointed out in the claims.

In the accompanying drawings, Figure 1 is a perspective view of my improved motor. 25 Fig. 2 is a rear elevation. Fig. 3 is a detached view of the band-wheel and the sliding frame, illustrating more clearly the connection and operation of the parts.

Like letters are used to indicate corresponding parts in the several figures.

Referring to the drawings, A designates the base or bed of the machine, having standards or uprights B B, extending up from the rear end. These standards or uprights are suitably 35 braced or connected, and at their upper ends form journals or bearings for the ends of the shaft C. The latter has a grooved band-wheel, D, mounted thereon, and provided with an operating-handle, E, extending out from the 40 periphery of said wheel. A spring, F, is coiled on the shaft C, and has one of its ends connected to one of the uprights B, and its other end connected to one of the faces of the band-wheel D, so that when the latter is 45 turned the spring is wound sufficiently to cause the return of the wheel to its original position.

G designates a guide-post rising from the base or bed A and extending up a sufficient 50 distance for the sliding frame H to travel on, and then bent or curved down to connect with

one of the standards B, to which it is bolted. The frame H consists of the vertical part a, having a horizontal extension, b, at its upper end, and a cross-head, c, at the lower end, the 55 extension and cross-head being both perforated to work freely on the post G. A rope or strap, I, connects with the cross-head and extends vertically, so as to enter the groove of the wheel D, the other end of the same being 60 connected to a short shaft, J, within a recess or cut-out portion, d, of the wheel. This shaft J acts as a windlass or drum upon which the rope or strap I may be wound to take up slack, and also decrease the extent to which 65 the frame H is moved. The shaft is extended to one side of the wheel D, and provided with a ratchet, K, and an operating-handle, L, a pawl, M, attached to one side of the wheel D 70 engaging with the ratchet so as to hold the shaft in the adjusted position. Another rope or strap, N, is connected to a stud on the vertical part a of the frame H, and extends down around and in the groove of the band-wheel D, and connected thereto by a screw or 75 the like.

It will be observed that the ropes or straps I N are wound on the band-wheel in opposite directions, so that when the wheel is turned in one direction the strap I is wound on the wheel 80 and the strap N unwound, while when turned in the opposite direction the action is just the reverse.

At the outer end of the horizontal part b of the frame H is detachably secured the upper 85 end of the dasher-shaft O, which may be provided with a dasher, as shown in the drawings, or with a clothes pounder or rubber of any suitable construction, accordingly as the motor is employed for churning or washing. When 90 the motor is employed for washing purposes, the spring F should be strong enough to give force to the downward movement of the shaft O; but in churning this is not found necessary.

In place of the handle E for operating the 95 wheel D, I may attach a pitman and treadle to the same, for operation by foot-power, as found convenient and desirable. I have not shown this arrangement, since it will appear so obvious an expedient to any one that illustration thereof seems unnecessary.

The operation of my invention will be read-

ily understood from the foregoing description, taken in connection with the annexed drawings. When the wheel D is turned rearwardly, the coils of the spring F are drawn upon, and 5 the strap I wound in the groove of said wheel, causing the frame H to slide or move vertically on the post G. As the frame is moved it carries the shaft O with it until the strap I has reached the limit of its length, when the 10 wheel D is allowed to return to its original position under the action of the spring F and the preponderance of the weight of the frame H, the latter carrying the shaft O, with its dasher or pounder, downward. This operation 15 may be repeated as often as desired until the work has been completed, the churning or washing being effected by the repeated action of the dasher or pounder.

It will be observed that very little friction 20 is produced by the operation of the motor, consequently there will be little wear on the parts. The power required to drive the motor need not be very great, for the only force that is expended arises on the turning of the 25 wheel backward, since the spring and weight of the frame is sufficient to return the same to its normal position.

By means of the shaft or windlass J the 30 strap or rope I may be wound thereon to decrease its length and correspondingly decrease the upward movement of the frame H, for the purposes well known in the art.

It will be apparent that I may apply my improved motor to various uses without departing 35 from the spirit of the invention.

Having described my invention, I claim—

1. In a motor, the combination, with the 40 sliding frame, of the grooved band-wheel, means for operating the latter, and straps, ropes, or bands connecting the drive-wheel to the sliding frame and wound in opposite directions on said wheel, for the purpose set forth.

2. In a motor, the combination, with the 45 sliding frame, of the grooved band or drive wheel, straps or ropes connecting the latter with the frame and wound on the wheel in opposite directions, and a spring connected to the wheel and arranged to be wound up by 50 the movement of the same in one direction, for the purpose set forth.

3. In a motor, the combination, with the stationary guide-post, a sliding frame moving on the post and carrying the dasher-shaft, of the band-wheel, straps or bands connecting 55 the upper and lower ends of said sliding frame to the wheel and wound thereon in opposite directions, and means, substantially as described, for operating said drive-wheel, as and for the purpose set forth. 60

4. In a motor, the combination, with the stationary guide-post, and a sliding frame moving on the post and carrying the dasher-shaft, of the band or drive wheel, straps, ropes, or bands connecting the upper and lower ends 65 of the frame to the band or drive wheel and wound thereon in opposite directions, one of said straps, ropes, or bands being adjustable in length, a spring connecting with the band or drive wheel, and operating means for the 70 latter, for the purpose set forth.

5. In a motor, the combination, with the base or frame having uprights or standards at one end, a shaft journaled in the standards or uprights, a drive or band wheel mounted 75 on the shaft, and a spring coiled on the shaft and connecting at one end with one of the standards and at the opposite end with the drive or band wheel, of the guide-post, a frame sliding on said post, ropes or straps connecting the upper and lower ends of the frame to the band or drive wheel and wound thereon in opposite directions, for the purpose set forth. 80

6. In a motor, the combination, with the 85 sliding frame carrying the shaft, of the drive or band wheel, ropes or straps connecting with the upper ends of the frame and attached to the band or drive wheel, one of the ropes or straps being attached to a short shaft or windlass, so as to be wound thereon to decrease its 90 length, for the purpose set forth.

In testimony that I claim the foregoing as my own I have hereto affixed my signature in presence of two witnesses.

THOMAS WELLINGTON HOGSETT.
